Atty's.

UNITED STATES PATENT OFFICE.

GEORGE NOTT, OF SWANSEA, ENGLAND.

ACETYLENE-GAS GENERATOR.

1,414,329.

Specification of Letters Patent. Patented Apr. 25, 1922.

Application filed January 29, 1916. Serial No. 75,148.

To all whom it may concern:

Be it known that GEORGE Nott, engineer, a subject of the King of Great Britain and Ireland, residing at Vincent Works, Picton 5 Place, Swansea, Glamorganshire, England, has invented certain new and useful Improvements in Acetylene-Gas Generators, of which the following is a specification.

This invention relates to acetylene gas 10 generators in which the carbide chamber is submerged in or located below the water level of a water tank or receptacle from which water is fed to the carbide through a tube usually arranged vertically in the 15 centre of the carbide chamber, or through an aperture or apertures in the side of the chamber, the feed being controlled by the gas pressure in the said chamber.

It has been found that with generators of 20 this type uniform production of gas with accompanying steady and constant flow direct from the generator to the burner is only attainable when the water inlet to the carbide is suitably restricted. Hitherto practical 25 considerations have prevented the inlet aperture being made as small as it should be to obtain the best results, the difficulty being that a small aperture readily clogs up so that the supply of water to the carbide 30 is rendered uncertain or is liable to stop entirely after the apparatus has been for a short time in use.

Now this invention has for its object to enable the feed water inlet to be restricted 35 to any desired extent for the purpose aforesaid without danger of clogging and consists in mounting a clearing rod or pin in the feed water aperture, and in supporting said rod or pin by a float in such manner 40 that it is reciprocated by the movements of the float as the water level varies in the tank under the influence of the gas pressure.

The invention is hereinafter described with reference to the accompanying drawings in which—

Fig. 1 is a sectional elevation of an acetylene gas generator in which the water inlet to the carbide is provided with a clearing rod in accordance with this invention 50 and

Figs. 2 and 3 are similar views to Fig. 1 showing modified constructions of clearing devices.

The generator shown in Fig. 1 comprises 55 an outer water receptacle or feed tank a

with a closed carbide chamber *b* submerged therein and having a central water feed tube *c* extending upwards into the chamber, and a gas outlet tube *d* extending from the top of the chamber *b* and communicating with the burner. Through the feed tube *c* which terminates in a contracted feed aperture *c*¹, the clearing rod or pin *e* is arranged to pass and is carried on a float *f* located in a water space provided in the feed tank directly below the carbide chamber *b* which has a raised bottom *b*¹. At its upper end the rod *e* may be bent as shown or provided with a suitable head to prevent its withdrawal from the aperture in the top of the feed tube.

In this form of generator the carbide chamber *b* is shown closed at the top by a removable cover *b*¹ secured in position by pivot bolts and wing nuts *b*², an india rubber or other suitable washer *b*³ being interposed between the cover and carbide chamber to form a tight joint.

When the feed is effected through an aperture in the side of the carbide chamber which is possible when the usual sealing bell *g* is employed as illustrated in Fig. 2, the clearing rod or pin *e* is reciprocated by the float *f* through a lever *h* or suitable rod and lever connections.

In the larger sizes, in order to deal with large quantities of carbide, it may be advisable to feed at more than one point but the clearing rods or pins for the feed apertures could be operated by a single float.

In this case, the carbide chamber *b* is open at the top and closed by the usual sealing bell *i* from the top of which the gas is conveyed by a pipe *j*.

It will be readily understood that the arrangement of the clearing rod and float may be varied.

On reference to Fig. 3 it will be seen that the float *f* may be on the surface of the water above the carbide chamber *b* in which event it could be connected to the clearing rod *e* by suitable means such as rod *k* and lever *l* to impart the necessary motion to the rod.

By the action of the moving rod or pin *e* as described the feed water tube *c* is kept clear and the feed aperture *c*¹ can be so proportioned that the production of gas without abnormal fluctuations is ensured.

Generators of the type described can be 110

connected with burners for lighting generally, and are particularly applicable to acetylene flares or torches.

What he claims and desires to secure by 5 Letters Patent is:—

In combination with a water tank, a carbide chamber submerged in the water of said tank, and having an inlet for the water, and a clearing rod passing through the inlet and restricting, but not closing, the same, which inlet is maintained permanently open, the water delivered to said per-

manently open inlet being subjected to the pressure of the gas in the carbide receptacle, whereby the feed of water is controlled, and means for automatically reciprocating said rod to keep the inlet opening clear, said means being operated by the variations in the level of the water in the tank under the influence of the gas pressure, substantially as described. 15 20

In testimony whereof he has affixed his signature.

GEORGE NOTT.
